UNITED STATES PATENT OFFICE

MORRIS J. STONE, OF WICHITA, KANSAS

PROPELLER

Application filed January 12, 1929. Serial No. 332,058.

This invention relates to propellers for aeronautical machines and the primary object is to provide an all metal propeller which can be constructed in an inexpensive and expeditious manner, the propeller consisting of certain parts and combination of parts which can be adjusted or caused to assume proper relative positions and then welded into an integral whole. The units or parts of the propeller can be made up and blades adjusted to the proper angle before the welding operation takes place and should a blade break, the parts are so constructed that the blade can be easily removed and a new one substituted.

15 The method of constructing the propeller as well as the details of construction of the various parts will be apparent by reference to the following description in connection with the accompanying drawing in which:

20 Fig. 1 is a front view of a propeller constructed in accordance with my invention.

Fig. 2 is a disassociated view of a tubular connector of the two propeller blades and a portion of one of the propeller blades.

25 Fig. 3 is a disassociated view of the blade connector, the hub, the sleeve and a portion of one of the propeller blades and

Fig. 4 is a cross-sectional view through one of the propeller blades.

30 The central member or blade connector is shown as comprising a cylindrical tube 1 having alining orifices 2 and 3 at its middle portion through which a transverse tubular hub 4 projects having extended ends 5 and

35 6. The member 1 connects the two propeller blades 7 and 8. Each blade has a constricted end 9 receivable in the end of the member 1 so that the shoulder 10 abuts against the end of the tube. A sectional cover and a reen-

40 forcing sleeve is receivable over the tube. It consists of two members 11 and 12 having semi-cylindrical inner faces 13 and 14 with reenforced middle portions 15 and 16 and half round notches 17 and 18 to fit over the ends of the projections of the hub. The hollow propellers may be reenforced by longitudinal braces 19.

In assembling the propeller parts, the hub 4 is inserted in the member 1, the ends 9—9 of the propeller blades are inserted in the

ends of the member 1, then the members 11 and 12 are slipped over the member 1 with their ends abutting against the shoulders 10—10. The propeller blades are then turned on their axis to provide the proper angle. The ends of the member 1, the shoul- 55 dered portions of the propeller blades and the ends of the members 11 and 12 are now welded together at one operation at each end and the ends of the hub are welded to 60 the members 11 and 12. The longitudinal edges of the members 11 and 12 are also welded together. The propeller is now com- 65 plete.

It provides in effect an integral structure 65 requiring no bolts, screws or other fastening devices. The welded joints, of course, being susceptible of being smoothed off so that unbroken symmetrical lines will appear throughout the entire propeller and with 70 such construction, an entirely all metal propeller is provided.

What I claim and desire to secure by Letters-Patent is:—

1. An aeronautical propeller comprising 75 two propeller blades, a connector, a cover for the connector, welded joints connecting the connector, the cover and each blade, and a hub passing through the connector and the cover and welded to the cover.

2. An aeronautical propeller comprising 80 two propeller blades, a connector, a cover for the connector, welded joints connecting the connector, the cover and each blade, and a hub passing through the connector and the 85 cover and welded to the cover, the cover consisting of two complementary longitudinal members embracing the connector.

3. An all metal hollow propeller comprising 90 a connector, hollow propeller blades having ends receivable within the ends of the connector, two longitudinal cover members co-extensive with the length of the connector having its ends welded to the propeller blades, and a hub passing transversely 95 through the cover and the connector.

4. An all metal hollow propeller comprising 100 a connector, hollow propeller blades having ends receivable within the ends of the connector, two longitudinal cover members

co-extensive with the length of the connector having its ends welded to the propeller blades, and a hub passing transversely through the cover and the connector and welded only to the cover.

5. An all metal propeller comprising a tubular connector, a hub carried thereby, a sectional cover about the connector through which the ends of the hub project and propeller blades welded to the connector and the cover.

6. An all metal hollow propeller comprising a tubular connector, a hub passing through the center of the connector having a shoulder overlapped by a portion of the connector, hollow propeller blades having constricted ends telescoped into the ends of the connector and a two piece cover embracing the connector having openings surrounding the ends of the hub, the cover having its greatest diameter at its middle portion, the cover being welded at its ends to the blades, the hub being welded to the cover.

In testimony whereof I affix my signature.
25 MORRIS J. STONE.
